HOT-WATER HEATING SYSTEM.

1,114,247.

Specification of Letters Patent. Patented Oct. 20, 1914.

Application filed December 24, 1909. Serial No. 534,812.

To all whom it may concern:

Be it known that I, JOSEPH W. GAMBLE, a citizen of the United States of America, residing in the city and county of Philadelphia, in the State of Pennsylvania, have invented a certain new and useful Improvement in Hot-Water Heating Systems, of which the following is a true and exact description, reference being had to the accompanying drawings, which form a part thereof.

My present invention relates to heating systems in which the heating medium is hot water.

15 The object of the invention is the production of a simple, reliable and effective heating system in which a heater like the well known open feed water heaters for heating boiler feed water or the like may be advantageously employed for heating the water circulated through the radiators by the direct action on the water of the steam. In the open feed water heaters referred to, a heating chamber is provided into which 20 the water to be heated, and steam for heating it, are both admitted, suitable overflow connections being provided to insure the presence of a steam space in the upper portion of the chamber.

30 The various features of novelty which characterize my invention are pointed out with particularity in the claims annexed to and forming a part of this specification. For a better understanding of the invention, 35 however, and the advantages possessed by it, reference should be had to the accompanying drawings and descriptive matter in which I have illustrated and described several of the forms in which the invention 40 may be embodied.

45 Of the drawings, Figure 1 is a diagrammatic elevation of one form of apparatus in which my invention may be embodied. Fig. 2 is a sectional elevation of an overflow connection for the heater which may be employed. Fig. 3 is a sectional elevation of one of the loaded valves which may be employed with the system shown in Fig. 1. Fig. 4 is a diagrammatic elevation of a portion 50 of a system differing in some respects from those shown in Figs. 1, 2 and 3. Fig. 5 is a view, similar to Fig. 1, showing a modification differing in some respects from

those shown in Figs. 1 and 4, and Fig. 6 is a view showing a slight modification of the system shown in Fig. 5.

In the drawings showing different modifications of the invention similar parts are designated by the same reference symbols throughout.

60 Referring first to the apparatus shown in Figs. 1, 2 and 3, A represents the heater proper which is of the type in common use and well known as open feed water heaters. As shown, it comprises a chamber having a 65 steam inlet pipe B leading to the chamber through an oil separator B', as is usual, a water inlet pipe C leading into the upper end of the chamber, splash trays or baffles D located in the upper portion of the chamber beneath the discharge from the pipe C, an outlet pipe E for hot water, and an overflow outlet F for preventing the water level in the chamber from rising above the outlet F. As shown, the outlet F leads into a receptacle F' from the bottom of which leads an escape pipe F², the pipe F² being controlled by a valve F³ which is operated by a float F² to which it is connected through a rock shaft F⁵ mounted within the chamber 70 75 F'. From the upper end of the heater leads the standpipe G, controlled by the loaded relief valve G', as is usual, to limit the steam pressure in the heater.

80 The outlet pipe E from the heater is connected to the inlet of a circulating pump X which is shown as a centrifugal pump and may be driven by an electric motor or other driving mechanism not shown. The outlet from the pump X is connected to the 85 pipe H which carries the water moved by the pump to the radiators K. The pipe H includes one or more suitable check valves H' and is connected at some suitable point to an expansion tank J by the branch pipe 90 J'. The radiators K have their inlets connected by pipes K' to the supply pipe H. The outlets of the radiators are connected by pipes K² to the return pipe L. The usual hand regulating valves K³ should be provided in the outlet connections K² or the inlet connections K', or preferably in both connections of the radiator.

95 In the form shown in Fig. 1, the pipe L and the pipe H beyond the radiators are 100 105 each connected through the U shaped seal

pipe M to the water inlet pipe C of the heater. Adjacent the seal pipe M a loaded valve O is placed in the pipe L and a similar loaded valve P is placed in the pipe H. The purpose of each of the valves O and P is to close the pipe in which it is placed except when the pressure in the pipe back of the valve rises to a predetermined value. Many different forms of valves may be used for this purpose. In the form of the valve O, shown in Fig. 3, the inlet O' and the outlet O² of the valve are separated by a valve seated port O³ controlled by the valve disk O⁴. The latter is normally held on its seat by a spring O⁵, the tension of which may be adjusted by a threaded spindle O⁶. As before indicated, the valve P is, or may be, the same in design as the valve O.

In the operation of the apparatus shown in Fig. 1, water is drawn from the heater through the pipe E by the pump X and is forced by the latter through the pipe H. When the valves K³ for one or more of the radiators are open, water from the pipe H flows through the radiators and thence into the pipe L from which it passes through the valve O, seal pipe M and the pipe C back to the heater. Water thus entering the heater is heated or reheated by steam admitted to the heater through the pipe B. The tension of the spring O⁵ of the valve O is adjusted to such a point that the valve disk will rise and permit water to flow through the valve when the pressure of the water entering the valve rises to a predetermined pressure, the tension being sufficient to prevent the valve from opening under the head of the water filling the radiators. In consequence, the valve keeps the radiators filled with water but opens to permit the circulation through the radiators when the pump X is in operation. The valve P is set to open at a pressure slightly above that at which the valve O opens. In consequence, the valve P is normally closed while the valves K³ are all open. When by reason of the closure of the valves K³ of all or a portion of the radiators, it becomes impossible to pass any or a portion of the water circulated by the pump X through the pipe L and the pressure at the end of the pipe H remote from the pump rises accordingly, the valve P opens to permit the circulation to be maintained.

Instead of employing a loaded valve to prevent too free a flow of water away from the radiators, a looped pipe Q may be employed to connect the pipe L to the seal M as shown in Fig. 4. It will be understood that the top of the loop Q is carried a suitable distance above the tops of the radiators K. To prevent the looped pipe Q from siphoning the water out of the radiators a vent connection should be made to the upper end of the loop Q. In Fig. 4 the vent connection is formed by a pipe R running

from the top of the loop Q to the heating chamber of the heater A.

Similarly as in Fig. 1, the valve P may be replaced by a loop U, as is also shown in Fig. 4. If the loop U is employed in conjunction with a loop Q between the seal pipe M and the pipe L, as shown in Fig. 4, the top of the loop U should preferably be placed a considerable distance above the top of the loop Q. The top of the loop should be suitably vented as by a branch pipe R' connected to the pipe R.

With the forms of the invention shown in Figs. 1 and 4, the circulating pump must work against the head due to the elevation of the radiators above the heater, and no advantage is had in the operation of the pump from the head of water passing through the return pipes. In some cases this loss of head may be objectionable, and in Fig. 5 I have shown an arrangement by which this loss of head may be avoided. In the form of the invention shown in Fig. 5, the heater is located above the level of the radiators and in consequence the only head of water against which the circulating pump must work is that due to the difference in elevation between the water level in the tank and the top loop of the return connections which need be only a few feet, plus, of course, the apparent head due to the frictional resistance to the flow of water through the pipes. In this form of the invention no loaded valve is necessary in the return pipe L as the disposition of the pipe consequent on the superior elevation of the heater prevents the radiators from draining through this return connection; though of course it is desirable to employ some arrangement of pipe connection or loaded valve for increasing the resistance to the flow of water through the extension of the pipe H forming a bypass around the return pipe L when such extension is employed as hereinafter described.

In the form of the apparatus shown in Fig. 5 a portion of the pipe H² is carried above the upper point of the pipe L and the water in the pipe C. This extension H² is vented at its upper level as by the pipe H² running to the heater tank.

In Fig. 6 a loaded valve P is employed in the pipe H as in Fig. 1.

It will be apparent to those skilled in the art that the heating system disclosed is simple and effective, and that it permits the effective utilization, and without change, of a type of water heater which is in general effective utilization, and without change, of development. The excess water constantly escaping from the heater through the overflow connection F in normal operation due to the condensation of the steam admitted for heating the water may be either turned to waste or preferably used for the various

purposes for which hot water is needed. For instance it may be used as a source of feed water supply for steam generating boilers. The steam by which the water is heated may advantageously be exhaust steam from pumping engines or the like where such a supply is available, and in such cases the use of steam for heating water for hot water heating systems is preferable under many circumstances to the use of steam in a steam heating system for heating the buildings or the like which are to be heated.

For some purposes, as to facilitate filling the system initially with water, or to replenish the water supply from time to time when water is drawn from the heating system for use for any purpose faster than water is supplied by the condensation of the steam, it may be desirable to provide means for always insuring a minimum water level in the heater. In Fig. 1 I have shown an arrangement for this purpose comprising a float W carried by a rock shaft W' journaled in an extension A' of the heater and provided with an external arm W^2 . The arm W^2 is connected by a rod W^3 to a valve Y in an auxiliary or make up water supply pipe Z . The arrangement is such that when the water level falls to some predetermined level as that indicated by the line W^4 , the valve Y will open, but will be closed by float W when the water level is above the line W^4 .

While in accordance with the provisions of the statutes, I have herein illustrated and described several of the forms in which the invention may be embodied, it will be apparent to those skilled in the art that many changes may be made in the apparatus shown without departing from the spirit of the invention, and I do not wish the claims hereinafter made to be limited to the particular forms of apparatus disclosed more than is made necessary by the state of the art.

Having now described my invention, what I claim as new, and desire to secure by Letters Patent, is:

1. In a hot water heating system, the combination, with a water heater having a heating chamber provided with steam and water inlets, a water outlet, and an overflow connection for limiting the height of the water level in the heater, of the radiators, a circulating pump for pumping the water through the radiators from the water outlet of the heater, and return connections between the outlets of the radiators and the water inlet

of the heater arranged to prevent the passage of water from the radiators into the 60 heater, except when the water in the radiators is under the pressure due to the operation of the pump in forcing water through the radiators, and a bypass about the radiators through which water may pass from the 65 pump to the inlet of the heater, said bypass being arranged to prevent the passage of water through it except upon the rise in pressure due to the closure of some or all of the radiators against the passage of water 70 through them.

2. In a hot water heating system, the combination with a water heater having a heating chamber provided with steam and water inlets, a water outlet and an overflow connection for limiting the height of the water in the heater, of the radiators, a circulating pump for pumping water through the radiators from the water outlet of the heater, a pipe connecting the outlets of the radiators 80 to the water inlet of the heater, a loaded valve in said pipe for preventing the passage of water from the radiators into the heater except under pressure due to the operation of the pump in forcing water 85 through the radiators, a pipe forming a bypass about the radiators and said loaded valve, and a loaded valve in said bypass set to open only when the pressure back of it is higher than that at which the first mentioned loaded valve opens.

3. In a hot water heating system, the combination with a water heater having a heating chamber provided with steam and water inlets, a water outlet and an overflow connection for limiting the height of the water in the heater, of the radiators, a circulating pump for pumping water through the radiators from the water outlet of the heater, a pipe connecting the outlets of the radiators to the water inlet of the heater, including provisions for preventing the passage of water from the radiators into the heater except under pressure due to the operation of the pump in forcing water through the 105 radiators, a pipe forming a by-pass about said radiators, and a loaded valve in said by-pass set to open only when the pressure back of it is higher than that in the radiators when the water is flowing therethrough 110 in normal operation.

JOSEPH W. GAMBLE.
